(57) **CLAIM**

The ornamental design for a personal mobility vehicle, as shown and described.

DESCRIPTION

FIG. 1 is a front, top, and left side perspective view of a personal mobility vehicle of our design;

FIG. 2 is a rear, top, and right side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

All features illustrated in broken lines form no part of the claimed design. Dash-dot lines illustrate an unclaimed border.

1 Claim, 8 Drawing Sheets

US D1,003,365 S
